(57) **CLAIM**

The ornamental design for a fence rail alignment fixture, as shown and described.

DESCRIPTION

FIG. 1 is a top front perspective view of my new fence rail alignment fixture;

FIG. 2 is a bottom front perspective;

FIG. 3 is a front elevation;

FIG. 4 is a rear elevation;

FIG. 5 is a right side elevation, the left side elevation being a mirror image;

FIG. 6 is a top plan view;

FIG. 7 is a bottom plan view; and,

FIG. 8 is a sectional view taken on the line 8—8 of FIG. 6.

The broken line showing a portion of a fence post in FIG. 1 is for illustrative purposes and forms no part of the claimed design.
